J. F. IRELAND

ELECTRIC SIGN

Filed May 31, 1927

Inventor:

John F. Ireland;

By *Tobiah W. Landolt*,

Attorney.

Patented Nov. 13, 1928.

1,691,520

UNITED STATES PATENT OFFICE.

JOHN F. IRELAND, OF PENNVILLE, INDIANA.

ELECTRIC SIGN.

Application filed May 31, 1927. Serial No. 195 267.

The object of my present invention, broadly speaking, is to provide a sign, which is adapted to be electrically lighted, the same being strong and durable in construction, exceptionally light in weight, very attractive in appearance and artistic in effect, easily placed in operative position, and which can be manufactured, sold, and installed at a comparatively low price.

More specifically stated, my object is to provide a sign composed of a frame in which all the parts thereof are integrally united and inclosed, with the frame filled in with fabric so treated that it will be both translucent and water-proof, and not subject to deterioration, or damage, through ordinary climatic or usage conditions and at the same time adapted to transmit a maximum of illuminated brilliance; and having means for supplying electric light to the interior of the sign to vividly display the characters which may be printed upon the sign or advertising a decorative purpose; and containing various other desirable features, all of which will be made apparent in the course of the specification.

One means for carrying out the principles of my invention in a practical manner, is shown in the accompanying drawings, in which—

Figure 1 is a side elevation of my complete sign, showing the same as suspended from a wall and in operative position. Figure 2 is a perspective skeletonized view of the frame alone. Figure 3 is a top plan view of the sign. Figure 4 is a cross section taken, for instance, on the line 4—4 of Fig. 3. Figure 5 is a detail view of one corner portion of the sign, simply showing the attachment of the fabric to the frame. And Figure 6 is a detail view of the shaft alone, by which the sign is supported whereby it may swing.

Similar indices denote like parts throughout the several views.

In order that the construction, the operation, and the several advantages of the invention may be more fully understood and appreciated, I will now take up a detailed description thereof, in which I will set forth the same as comprehensively as I may.

The invention comprises a skeletonized double frame which is formed by the upper members 1 and 2; the lower members 3 and 4; the inner end members 5 and 6; and the outer end members 7 and 8. One side of the

double frame is formed by the members 1, 3, 5 and 7. The other side of the frame being formed by the members 2, 4, 6 and 8.

Said side members are spaced apart and are connected by the straight cross members 9, 10, 11, 12, 13, 14 and 15, and by the V-shaped cross-member 16. Each of said members, 1 to 16 inclusive, is formed of tubing or of rather heavy stiff wire stock, and they are all integrally united at their junctures with each other whereby a complete double frame is formed substantially as shown in Fig. 2.

The frame thus formed is completely covered with fabric, preferably rather thin and transparent linen gauze, forming the faces or sides 17 and 18. The former being secured to the members 1, 3, 5 and 7, and the latter to the members 2, 4, 6 and 8. The edges of the sides 17 and 18 being simply coiled around said members of the frame, where they are retained by an adhesive, such as glue, shellac, or so-called "aeroplane dope". In like manner the fabric top 19 is secured at its edges to the members 1 and 2; the bottom fabric 20 is likewise secured to the members 3 and 4; and the end fabrics 21 likewise extend between the members 5—6 and 7—8, to which they are secured in same manner as the members 17 and 18. In fact the top, bottom, and ends may be formed of a single length of fabric.

In the center of the bottom 20, between the members 3, 4, 12 and 13, an opening should be formed whereby access may be had for one's hand into the interior of the sign. Also in the center of the top 19 is a small aperture *a*, which is covered by an arched cap 22, which is open at each end, in order to provide ventilation for the interior.

After being attached in place the various members of the fabric mentioned are covered with a transparent fluid or varnish, such as that used on the wings of aeroplanes, such as is commonly called "aeroplane dope," which is a clear liquid resembling shellac, glue, paste or varnish, which has the characteristic of hardening quickly, and of stretching the fabric tightly, and when dry is absolutely waterproof, and will not dissolve or disintegrate by weather conditions. Several applications, or coats, of said dope should be applied to the fabric in order to attain the desired consistency for service.

Any advertising or other matter may be printed or painted upon the fabric, either before or after the application of the dope,

or even between two layers of said dope. Likewise any desired color may be given to the fabric. Also the characters, such as John Doe shown in Fig. 1, may be applied on the white background of the members 17 and 18; or the letters may be left white and the background may be colored or painted in as desired.

After said fabric members are located, as set forth, then the various corners of the sign are covered with rather heavy tape 35, thereby providing reinforcement and covering the joints where the fabric members overlap the frame. Said tape being laid to follow the outlines of the frame members and following the contour thereof.

A pleasing and artistic effect is given by having the tape of a color distinctively different from that of the fabric.

Numeral 23 denotes a shaft which is attached at one end to the cross member 9, resting in the angle of the member 16 and secured thereto, and extends under the member 15, and then extends back some distance beyond the inner end of the sign.

Said shaft has a notch 24 formed across its rear portion.

Secured to the wall A is a plate 25, from which extends outward the tubular hanger-arm 26, in which fits the shaft 23. A set-screw 27 is threaded into the arm 26, with its point adapted to enter the notch 24 whereby the shaft 23 may rotate a limited distance but can not be moved endwise while the set-screw is therein.

Located inside the body of the sign is one or more electric lamps, as for instance the lamps 28, 29 and 30, which are connected by the wires 31 and 32, with a lead-in wire 33 extending from one, and a second wire 34 forming the return circuit. Said wires extend back through the end of the sign, from which they extend to a source of electricity, in any well known manner. The sockets of said lamps may extend up from the cross members 11, 12, 13 and 14, or they may extend down from the cross members 9, 10, 15 and 16 employing any number of lamps desired.

Said strip 40 also acts as a brace to further stiffen the sign.

Extending out from the center of the

cross member 10 is an eyelet 36 which, when the sign is in the position shown in Fig. 1, has two guy-wires 37 extending therefrom, flaring apart therefrom, with their upper ends secured in eye-bolts 38 attached to the wall A.

When the sign is positioned and connected up as shown in Fig. 1, it is evident that if electric current be turned on to light the lamps, that while the lamps can not be seen from outside the sign, yet the sign will be lighted in all of its parts, thereby giving a very pleasing, artistic, and attractive appearance as a whole, and the advertisements on each side of the sign will stand out very clearly and distinctively.

I desire that it be understood that the sign may be made in various shapes and sizes, and of varying contour, without departing from the spirit of the invention or sacrificing any of the advantages thereof which are new and useful and which involve invention.

Having now fully shown and described my invention, what I claim, and desire to secure by Letters Patent of the United States, is—

A sign comprising in combination, two side members identical with each other and spaced apart parallel with each other and so formed of metal tubing, cross members rigidly connecting said side members and together with the side members forming a skeleton frame-work, a shaft secured to the upper cross members and located midway of and parallel with said side members and extending out there from at one end, an eye bolt mounted on said shaft, a brace strip secured at its ends to two of the lower cross members with its central portion attached to said eye bolt, fabric covering said frame-work and secured thereto, transparent material known as aeroplane dope applied to said fabric, advertising matter applied to said fabric, means for adjustably suspending the sign by said shaft, electric light fixtures located between said two sides of the frame, means for conducting electric current through said fixtures, and means for reinforcing the edges of the sign, all substantially as set forth.

In testimony whereof I have hereunto subscribed my name.

JOHN F. IRELAND.
